CLAIM

The ornamental design for a plumbing fixture, as shown and described.

DESCRIPTION

FIG. 1 is a perspective view from the front of my plumbing fixture.

FIG. 2 is a rear view of my plumbing fixture as shown in FIG. 1.

FIG. 3 is a top view of my plumbing fixture as shown in FIG. 1; and,

FIG. 4 is a right side view of my plumbing fixture as shown in FIG. 1, the left side view being a mirror image.

The broken lines in the Figures are for illustrative purposes only and form no part of the claimed design.

1 Claim, 4 Drawing Sheets

FIG. 3

FIG. 4
